UNITED STATES PATENT OFFICE.

PETER W. SCHWANDER, OF HOUSTON, TEXAS.

CHECK-BOOK.

1,222,037.

Specification of Letters Patent. Patented Apr. 10, 1917.

Application filed September 20, 1915. Serial No. 51,669.

To all whom it may concern:

Be it known that I, PETER W. SCHWANDER, a citizen of the United States, residing at Houston, in the county of Harris and State 5 of Texas, have invented certain new and useful Improvements in Check-Books, of which the following is a specification.

This invention relates to new and useful improvements in a check book.

10 As the ordinary check book is now formed, it is inconvenient to use, inasmuch as the check stub is located near the binding of the book and is comparatively inaccessible.

15 The object of this invention is to provide a check book having extra sheets, the outer margins of which are provided with stubs, corresponding to the checks and the remainder of said extra sheet is ruled in journal book form, to which the items may be transferred from said stubs, the extra sheet being removable along perforated lines and being provided with the perforations so that they may be transferred from the check book and bound into a loose-leaf volume. A complete 20 record in journal book form may thus be accurately and conveniently kept.

25 With the above and other objects in view, the invention has particular relation to certain novel features of construction and arrangement of parts and use, an example of which is given in this specification and illustrated in the accompanying drawings, wheren—

30 Figure 1, shows a fragmentary plan view 35 of the check book in open position.

Fig. 2, shows an edge view thereof in closed position, and

35 Fig. 3, shows a plan view of the stub journal sheet the reverse side of which is also 40 shown in the rear thereof.

Referring now more particularly to the drawings wherein like numerals of reference 45 designate similar parts in each of the figures, the numeral 1, refers to the covering, in which is bound, in the ordinary manner, a plurality of check sheets 2, which are separated by perforated lines into the checks 3, 3, 3, of the ordinary and well-known form. Underneath said check sheets and bound 50 therewith, is a plurality of stub journal sheets 4. These sheets 4, are considerably longer than the check sheets 2, as shown in Figs. 1 and 2, and the extended margins thereof are formed by suitable ruling, into

stubs, corresponding to the ordinary check 55 stub, each stub being numbered to correspond with its respective check. When the check book is in use, the stub portion of the upper sheet 4, will be always exposed, so that when a check is written, the corresponding 60 stub may be filled out in the usual way without inconvenience, and without folding back the stub sheets to come at the stub, as is usually required. When all of the stubs on a sheet have been filled out, the stub journal 65 sheet may then be torn out along the perforated line 5, and transferred to a loose-leaf volume, said sheet having the perforations 6, 6, to permit it to be secured in said volume. As before stated, all of the sheet 4, except the 70 stub portion is ruled into journal book form and the items of the check stubs may be readily transferred from said stubs to the proper accounts of the journal sheet proper. This operation can be very easy and con- 75 veniently done, inasmuch as all of the check stubs and the data contained therein are easily accessible to the accountant, being a part of the sheet 4. From the journal portion of the sheet 4, the accounts may be transferred 80 to the ledger in the usual manner. The reverse side of each sheet 4, may also be ruled into journal book form, if desired, so as to give space for a greater number of accounts, in cases where a large number of accounts is 85 kept.

What I claim is:

A device of the character described consisting of a plurality of sheets each separated by perforated lines into sections containing 90 check data, a plurality of consecutively arranged stub sheets all lying together and being underneath the perforated sheets and projecting beyond the free edge of the latter, all of said sheets being bound together in 95 book form and the underlying sheets being ruled into journal form and the projecting portion thereof forming the ordinary check stub, each stub sheet having a perforated line near the binding margin along which it 100 may be readily detached.

In testimony whereof I have signed my name to this specification in the presence of two subscribing witnesses.

PETER W. SCHWANDER.
